United States Patent Office.

JONAS P. CURTISS, OF NEW BRITAIN, CONNECTICUT.

Letters Patent No. 71,586, dated December 3, 1867.

IMPROVEMENT IN DEVICE FOR GRINDING CUTLERY.

The Schedule referred to in these Letters Patent and making part of the same.

TO ALL WHOM IT MAY CONCERN:

Be it known that I, JONAS P. CURTISS, of New Britain, county of Hartford, and State of Connecticut, have invented certain new and useful Improvement in Device for Forming and Finishing the Edges of Knives, &c.; and to enable others skilled in the art to make and use the same, I will proceed to describe by referring to the drawings, in which the same letters indicate like parts in each of the figures.

The nature of this invention will be understood from the specification and drawings.

The object desired to be attained by this invention is to facilitate in the execution of the grinding or shaping process, and to keep the grinding-surface of the stone perfectly true to act upon work presented to its action by a gauge.

I first construct a framework in front of a revolving grindstone. Upon this frame I arrange another sliding frame or bed, so that it may be adjusted, from time to time, closely to the action of the stone. Near the edge of this adjustable frame, and next to the edge of the stone, I arrange guide-pins, upon or against which a former-stock works, to give the proper shape to the blade of a knife, or other tool or instrument which it may be employed for grinding. This former is arranged in the under side of the stock, in or to which the tool, knife-blade, or other article, is held by means of screw-cams or other mechanical equivalents. In the accompanying drawings—

Figure 1 represents a bed-plate, which is designed to be arranged upon framework in front of a grindstone, so that it will, when in use, slide in a line towards or from the grindstone, and so that its nearness thereto can be easily and readily adjusted according to the wear of the stone.

Figure 2 is a side view of the stock in which the article desired to be ground into shape is placed and held, a top view of which is shown in fig. 2.

a is a sliding bed-plate, arranged upon ways, and adjusted by means of screws or their mechanical equivalents. *c* are pins, arranged in a parallel line upon and near the edge of the sliding adjustable bed *a*. *d* is a pattern-stock, provided with a groove in its under side, the shape of which is such as to present the article held thereon to the action of the stone, so as to produce the required shape. *e* are joint elevations, formed on each side of the stock. *f* is a finger-bar, secured between the elevations *e* by a pin, and having a screw or cam, *f'*, arranged in the back end thereof, for the purpose of firmly depressing the article between it and the stock, while the grinding is being performed. *h* are screws, which are turned firmly against the edge of the blades or tang of a knife-blade, while the grinding is performed. The groove-stock *d* is placed upon the centre-pin *c*, so that, when turned in one direction against the pin *c'*, it (the pin *c'*) will enter the groove, formed in the under side of the stock *d*, through a side slit, *i*, and, when turned to the left, or in the opposite direction of the first, against the pin *c''*, it will enter the groove through the slit *i'*.

The table or sliding bed-plate *a* is arranged upon ways, and its position relative to the action of the stone is graduated or regulated by screw-gauges or their mechanical equivalents.

Now, when the above mechanism is prepared, and the blanks are in readiness, the workman places one or more in the clamp-stock, and presses the stock, with its bed, gradually to the action of the stone, and moves the stock *d*, resting against the pins, in a line parallel with the grinding-surface of the stone, till one edge of the blades is ground to the desired pattern or shape; then, turning the stock steadily in the opposite direction about a half circle upon the pin *c*, will produce a true rounded end to the blades, and then, by moving it (the stock) back upon the pins *c*, the desired pattern or shape will be produced. Thus several blades can be ground into the desired pattern by one operation, and of uniform shape, and at the same time the stone is kept in perfectly true working order, which is a great desideratum in grinding or shaping knives or other like articles.

I believe I have thus shown the nature, construction, and operation of this device, so as to enable others skilled to make and use the same therefrom.

What I claim, therefore, and desire to secure by Letters Patent, is—

A device for forming and finishing the edges of knives, &c., substantially as described.
